UNITED STATES PATENT OFFICE

157,450

GAME BOARD

Eddie Parker Truesdale, Orangeburg, S. C.

Application January 19, 1948, Serial No. 143,859

Term of patent 14 years

(Cl. D34—5)

To all whom it may concern:

Be it known that I, Eddie Parker Truesdale, a citizen of the United States of America, residing at Orangeburg, in the county of Orangeburg and State of South Carolina, have invented a new, original, and ornamental Design for a Game Board, of which the following is a specification, reference being had to the accompanying drawings, forming part thereof.

Fig. 2 is a sectional view taken on line 2—2 of Fig. 1.

Fig. 3 is a bottom plan view.

Fig. 4 is a sectional view taken on line 4—4 of Fig. 1.

The dominant features of my new design are shown in solid lines in the drawing.

The cross hatching in Fig. 1 indicates colors red and green.

I claim:

The ornamental design for a game board, as shown and described.

EDDIE PARKER TRUESDALE.
